(No Model.)

T. F. CARLOS.
INVALID'S SUPPORT.

No. 555,894.

Patented Mar. 3, 1896.

UNITED STATES PATENT OFFICE.

TIMOTHY F. CARLOS, OF TRENTON, NEW JERSEY.

INVALID'S SUPPORT.

SPECIFICATION forming part of Letters Patent No. 555,894, dated March 3, 1896.

Application filed September 25, 1895. Serial No. 563,614. (No model.)

To all whom it may concern:

Be it known that I, TIMOTHY F. CARLOS, of Trenton, in the county of Mercer and State of New Jersey, have invented certain new and useful Improvements in Water - Closet Attachments; and I do hereby declare the following to be a full, clear, and exact description of the invention, such as will enable others skilled in the art to which it appertains to make and use the same.

This invention contemplates certain new and useful improvements in water-closet attachments.

The object of the invention is to provide simple and inexpensive means for affording support to an invalid or other person while using a water-closet seat, thereby relieving them of all strain and enabling them to easily sit or rise without undue exertion.

20 A further object is to provide an attachment of this kind by which medicine, toilet-paper, and the like can be kept conveniently at hand and wearing-apparel can be suspended within reach.

25 The invention will be hereinafter fully set forth and particularly pointed out in the claims.

In the accompanying drawings, Figure 1 is a view in perspective. Fig. 2 is a similar 30 view, slightly enlarged, showing the connecting-support in position. Fig. 3 is a cross-sectional view. Fig. 4 is a detail. Fig. 5 is a similar view showing a slight modification.

Referring to the drawings, A A' designate 35 two supports, which I have shown as consisting of two rectangular boards *a*, suspended at their upper ends from a horizontal rod *a'*, which latter can be secured to the wall of the water-closet or suspended from the ceiling 40 thereof. Each board is shown as having a bail *a*² with a central eye *a*³ to enable them to be moved toward or away from each other.

B B designate two loops or arm-rests, each 45 of which consists of a strip of heavy canvas, leather, or the like attached at its upper end *b* to the outside of one of the boards, its free end being provided with an eye or ring *b'*, which is designed to engage with any one of a series of hooks *b*² secured to the board. By this 50 means each loop can be lengthened or shortened to accommodate the different persons.

To the front longitudinal edges of these boards are secured hooks *C*, for supporting wearing-apparel thereon. The two boards supporting the adjustable loops are moved 55 toward or away from each other to accommodate different users; but this does not materially vary, and they usually hang within a short distance of each other.

D is a leaf or support which is hinged or 60 otherwise connected at one end to the lower end of board *A'*, and at its other end is provided with hooks *d*, designed to engage eyes *d'* of the other board, *A*, near the lower end thereof. When this leaf or support is not 65 desired it is turned up out of the way and rests against the board *A*. While I prefer to hinge this leaf to the board *A*, yet it may be provided with hooks at each end (see Fig. 5) to engage corresponding eyes. A drawer 70 *E* is attached to this leaf or support and may contain medicine or the like. Toilet-paper may be suspended from a hook *e* on the inner side of board *A'*.

It will be understood that changes may be 75 made without departing from the scope of my invention—as, for instance, the two supporting members to which the loops or arm-rests are secured may be made of canvas, leather, or any other suitable material, and 80 the leaf-support may be entirely dispensed with or used at pleasure.

I claim as my invention—

1. An attachment of the character herein described having two depending supports, a 85 loop or arm-rest for each of said supports having one end rigidly secured, its other end being provided with an eye or ring, and series of hooks extending from said supports with which the said eyes or rings of said loops 90 or arm-rests are designed to engage, substantially as set forth.

2. An attachment of the character herein described having two depending members, a shelf or support between the lower ends of 95 said members and removably secured thereto, and adjustable loops or arm-rests attached to the outer sides of said members, as set forth.

3. An attachment of the character herein described having two depending boards, loops 100 or arm-rests secured to the outer sides of said boards, a shelf or support pivotally connected

to the inner side of one of said boards and designed to engage the inner side of the other board at its free end, as set forth.

4. The combination with the suspending-
5 rod, of the two depending members adjust-
able thereon, hooks on the front edges of said
members, loops or arm-rests attached each
at one end to one of said members, its other
end being provided with an eye or ring, a se-
10 ries of hooks projecting from each of said
members and with which said eyes or rings

are designed to engage, and the shelf or sup-
port supported between the lower ends of
said members, as set forth.

In testimony whereof I have signed this 15
specification in the presence of two subscrib-
ing witnesses.

TIMOTHY F. CARLOS.
